United States Patent Office

Des. 195,552
Patented July 2, 1963

195,552

AUTOMOTIVE MIRROR BASE

Thurman F. Naylor, Wellesley, and Pierce Hollingsworth, Wayland, Mass., assignors to Standard-Thomson Corporation, Waltham, Mass., a corporation of Delaware

Filed Dec. 19, 1962, Ser. No. 72,906

Term of patent 14 years

(Cl. D14—6)

FIG-1

FIG-3

FIG-2

FIG-4

FIG-5

FIGURE 1 is a perspective view of an automotive mirror base showing our new design.

FIGURE 2 is a top view thereof.

FIGURE 3 is an end view thereof, looking at the right hand end of FIGURE 1.

FIGURE 4 is an end view thereof, looking at the left hand end of FIGURE 1.

FIGURE 5 is a side elevational view thereof.

We claim:

The ornamental design for an automotive mirror base, substantially as shown.
